CONE TYPE WRINGER

Frederick A. Speik, South Pasadena, Calif.

Application November 8, 1937, Serial No. 173,295

8 Claims. (Cl. 15—263)

My invention relates to a type of wringer for mops known in the trade as cone type in that an inverted cone with a large number of openings is suitably supported and in this cone a wet mop may be inserted, then by a twist on the handle the mop undergoes a twist in the cone, wringing the water from the mop. In this type of mop wringer, certain of these are designed to attach to the side of a pail or built in the side of a special receptacle. One of the disadvantages of this type resides in when a pressure is placed on the mop to wring the same frequently the pail or the receptacle is upset, thereby spilling the dirty water. This is mainly due to the pressure not being evenly distributed over the bottom of the pail in order to counteract the side pressure in wringing the mop.

An object and feature of my invention therefore is to incorporate with a cone type of mop wringer which has hooks to engage over the rim of a pail with the wringer fitting inside the pail, a supporting stand or leg structure securely attached to the cone wringer and engaging the pail or other receptacle in such a position that the downward thrust is in part transmitted to the bottom portion of the pail or receptacle and the construction causes this pressure to be in such a position that there is practically no danger of upsetting the pail or receptacle when wringing a mop and exerting a thrust through the mop handle in twisting the wet portion of the mop in the wringer. A further detail feature of my invention is making the stand or leg construction adjustable as to the cone type wringer so that the bottom or shoe portion will engage the bottom of the pail and be suitable for different sizes of pails, the shoe preferably engaging the pail adjacent the bottom and side opposite the hooks engaging over the rim. In another form of my invention the leg and shoe construction is rigidly secured to the cone type of wringer and made of the proper length for a certain size of pail. This however may be accommodated in pails of quite a number of different depths and sizes, as the hooks readily permit the change of inclination of the mop and the position in which the shoe engages the bottom of the pail.

Considered in more detail, other features of my invention include forming the cone type wringer of a combined helical and spiral winding of stiff wire to form a cone with the base upwardly and the apex at the bottom, the various coils or convolutions are then secured by longitudinal straps formed of wire welded to the various coils. A pair of these straps are provided

with hooks to engage the edge of a pail. In the adjustable form the legs have wire rods adjustable in a clamp having a bolt, the clamp being secured to the cone wringer on one side, such being the side having the hooks. In another type with the non-adjustable leg structure, the straps having the hooks may continue downwardly preferably diverging from the lower portion of the cone and having a connected shoe structure to engage the bottom of the pail.

Another feature of my invention involves providing the hook with a pivotal attachment to the cone and such may be done by linking the two arms of the hook to the upper turn or convolution of the wire forming the cone. This takes the place of a rigid hook and adapts the cone to conform to the shape and arrangement of hanging of a number of different sizes and shapes of pails.

In a modified construction I provide a telescopic leg assembly with a guide channel structure secured to the wire cone and have the legs slidably mounted in such guide with a pin and perforation connection. This affords a quick adjustment to pails of different depth without using any hand tools or the like.

My invention is illustrated in connection with the accompanying drawings, in which:

Fig. 1 is a side elevation of one form of my invention with the adjustable leg taken in the direction of the arrow 1 of Fig. 2.

Fig. 2 is a rear elevation taken in the direction of the arrow 2 of Fig. 1.

Fig. 3 is a side elevation of another form of construction having the non-adjustable legs taken in the direction of the arrow 3 of Fig. 4.

Fig. 4 is a rear elevation taken in the direction of the arrow 4 of Fig. 3.

Fig. 5 is an elevation of a pail broken away and showing one form of the mop wringer in an elevation.

Fig. 6 is a partial side elevation taken in the direction of the arrow 5 of Fig. 7 showing a hinged or pivoted hook.

Fig. 7 is a partial elevation taken in the direction of the arrow 7 of Fig. 6.

Fig. 8 is a front elevation of still another form in which the leg assembly is connected to the wire cone by a guide channel structure.

Fig. 9 is a partial side elevation taken in the direction of the arrow 9 of Fig. 8.

Fig. 10 is a partial rear elevation taken in the direction of the arrow 10 of Fig. 9.

Referring first to the construction of the cone wringer, such being designated by the numeral 55

- 11, this is preferably formed of a combined helical and spiral winding of stiff wire designated by the numeral 12, this having the base 13 uppermost and converging to the apex 14 at the bottom. 5
15 This winding commences with an upper coil or convolution 15 and a series of successively smaller turns or convolutions 16 ending in a terminal twist 17 at the bottom or apex.

These coils or convolutions are secured together by longitudinal straps 20 of which in Fig. 10 there are preferably two of these on diametrically opposite sides secured to each convolution crossed by the strap by spot welding, brazing or the like. There are also hook straps 21 which 15 slightly converge towards the bottom, these being likewise secured to the convolutions by welding or brazing and each has a hook 22 at the top, the hook terminating in a bead 23 to make a neat finish and lessen the chances of the cords 20 of the mop catching on the end of the hooks.

These hooks as shown in Fig. 5 engage over the rim 25 of a pail 26, the bottom of the pail being indicated at 27.

In the construction as shown in Figs. 1 and 2 I 25 provide a clamp assembly 30 secured to the wire wound cone, this clamp being fitted between the straps 21 having the hooks. The clamp includes an inside plate 31 fitting inside the winding of the cone and a clamping plate 32 on the inside, these 30 being secured together by a bolt and nut 33. If desired this may be adjustable up and down on one side of the cone or the inside plate 31 may be welded or soldered in a fixed position.

The leg assembly of Figs. 1 and 2 indicated as 35 35 comprise a pair of leg rods 36, this being shown parallel and fitting underneath the clamping plate and contacting directly a series of convolutions of the wire winding. The upper ends 37 preferably terminate below the base of the cone and below the hooks so that they do not 40 interfere with the attachment to the pail. These legs have a shoe construction 38 at the bottom indicated as having diverging arms 39, a reverse bend 40 and a transverse bottom strip 41 which 45 engages the bottom of the pail and at the ends may contact the side 26 of the pail approximately opposite the portion of the pail engaged by the hooks.

In the construction shown in Figs. 3 and 4 the 50 hook straps 45 are preferably parallel and spaced the desired distance apart. These are secured to the convolutions of the cone winding by welding, brazing or the like and are provided with hooks 46 at the top. The leg structure 47 is 55 formed integral and has leg rods 48 diverging from the lower ends of the strap portions 45, and is provided with a shoe 49 at the bottom, this being formed by angle bends 50, upwardly extending portions 51 meeting at an obtuse angle 60 52. This construction is intended so that it is to fit pails of approximately the same depth and when the hook engages the rim on one side, the reverse bend portions 50 are intended to engage the bottom and the side wall 26. However this 65 type of construction is quite suitable for a considerable range of pails as to depth and diameter.

In Figs. 6 and 7 I illustrate the hook as having a pivotal connection to the cone type of wringer. In this instance the hook is designated by the 70 assembly numeral 60. This has a pair of spaced arms 61, each bent to form an individual hook 62 with a transverse bar 63 engaging the ends of the individual hooks. Each of the bars 61 is formed with an eye 64 loosely wrapped around the 75 upper turn or convolution of the cone forming

the wringer proper. This construction may be used with the arrangement having the adjustable leg of Figs. 1 and 2 or the non-adjustable leg of Figs. 3 and 4, the rigid hook manifestly being omitted. This construction permits the cone 5 wringer to be suspended over the upper edge of a greater size range of pails and to be suspended in such a manner that the wringer is given proper support by the leg structure from the bottom of the pail. 10

As a characteristic of my invention it will be noted that when the mop wringer is attached to the rim of an ordinary size pail with the shoe at the bottom of the leg engaging the pail at substantially its opposite side, the axis of the 15 cone has an inclination, this usually being towards the center of the pail. When a person is wringing a mop they usually insert the wet mop centrally in the cone and with the handle at approximately the axis of the cone. Therefore 20 the downward pressure is substantially towards the center of the pail, the thrust by the hooks and the leg thrust through the hooks and the leg, thus on opposite sides of the center, this forming the center of thrust at substantially the 25 center of the pail and hence reducing the danger of upsetting the pail.

In Figs. 8, 9 and 10 I illustrate a modified construction by which there is a slip connection of the leg assembly and a guide channel structure for readily adjusting the leg for the depth of different pails and this without the use of any hand tools such as a wrench or the like. In this construction the cone wringer 75 is formed of a combination helical and spiral winding of 35 wire, the apex end 76 being at the bottom and the base 77 at the top. The upper convolution is indicated as terminating at 78. In the front I attach upwardly extending guide straps 79, there being a pair of these in which the lower ends 80 40 are quite close together and attached to one of the lower convolutions. These straps extend above the uppermost convolution and have a cross strap 81. This is slightly arched downwardly from the ends 82. Thus the cross straps 45 and the side straps are formed of one piece. At the back or rear of the cone wringer I also use a pair of rear straps 83 and 84. These straps as well as the front straps are secured to the coiled wire by spot welding or soldering or the like. The 50 straps are placed on the wires to intersect each convolution at substantially right angles. The strap 84 is indicated as attached at its top 85 to the upper convolution adjacent its ends 78.

The guide channel assembly 90 has a longitudinal web 91, opposite marginal flanges 92 and inwardly turned rims 93. The flanges are parallel and the web is attached to the various convolutions which it intersects at substantially right angles by soldering, or welding material indicated at 94. The flanges have a series of perforations 95. It will be seen therefore that the channels are open at the bottom and top, there being also an open space between the inner edges of the rims 93. 55

The leg assembly 100 includes a pair of parallel rods 101, each of which has an outwardly turned pin 102 at the top. The rods are parallel for a considerable part of their length and then each has a diverging leg section 103, both legs at the 70 bottom being joined by a transverse shoe 104. This shoe may be a straight section of wire having the corner bands 105 or may have a belt as shown in Fig. 4. If desired the leg and the shoe section may be made as shown in Fig. 2. The 75

pins fit in any pair of the perforations 95 in the flanges, these being opposite, the leg assembly is made of resilient wire having a natural tension to urge the pins outwardly. Therefore as the 5 rods 101 may be readily squeezed together to disengage the pins from any pair of perforations, the rod may be slid up and down in the channel guide, the pins thus give a thrust reaction to the channel guide and thus give a support for the 10 cone wringer in the bottom of the pail, the shoe assembly engaging the pail preferably on the side opposite to that to which the wringer proper is attached. In this illustration I show a hook assembly the same as indicated in Figs. 6 and 7 15 and designated by the numeral 60. This is fitted to one of the upper turns of the wire of the cone and centrally located above the channel guide. It will however be understood that I may use fixed hooks as illustrated in Figs. 1 and 20 2 or 3 and 4 in which the hooks would be formed integral with the rear straps.

Various changes may be made in the details of the construction without departing from the spirit or scope of the invention as defined by the 25 appended claims.

I claim:

1. In a device as described, a mop wringer having an inverted cone with means for attachment to the side of a pail or the like and a leg structure 30 connected to the cone and adapted to engage a part of the pail remote from the attaching means, the leg structure being adjustably connected to one side of the cone for a movement longitudinally of such side in a line between the base and 35 the inverted apex of the cone.

2. In a device as described, an inverted cone wringer for mops having a wire with a conical spiral coil with side straps intersecting the convolutions of the wire at substantially right angles 40 extending from a position adjacent the base towards the apex, the straps and the convolutions of the wire being attached together, a hook having a connection to one side of the cone adjacent the base, the hook being constructed for engaging a rim of a pail, a leg structure attached to one 45 side of the cone and extending downwardly from adjacent the hook, the leg having a shoe adapted to engage the bottom and side of a pail at a part remote from the side of the pail engaged by the 50 hook.

3. In a device as described and claimed in claim 2, the hook having a hinged or pivoted connection to an upper convolution of the cone adjacent the base whereby when the hook engages the side of 55 a pail there may be a slight angular adjustment of the cone in reference to the pail.

4. In a device as described, an inverted cone wringer for mops and having a wire with a conical spiral coil with side straps intersecting the convolutions of the wire at substantially right angles, said straps extending from a position adjacent 60 the base towards the apex, the straps and the con-

volutions of the wire being attached together, a leg structure adjustably attached to one side of the cone and extending downwardly substantially straight on one side of the cone towards the apex with a portion of the leg structure extending 5 below the apex, a shoe on the bottom of the leg structure to engage the bottom of a pail.

5. In a device as described and claimed in claim 4, a pivotal attaching means for fastening the base of the cone to the rim of a pail in alignment 10 with the leg structure, the adjustable attachment of the leg structure to the cone including a clamp assembly having an inside plate secured to the inside of the cone, an outside plate with means to slidably engage the leg structure and a bolt connecting the said plates together for a frictional engagement with said leg structure. 15

6. In a device as described and claimed in claim 4, a pivotal attaching means for attaching the base of the cone to the rim of a pail in alignment 20 with the leg structure, the adjustable attachment of the leg structure including a guide channel having opposite perforated flanges and secured to the outside of the cone structure, the leg including a pair of parallel spaced rods having resilient 25 means interposed normally tending to separate said rods and having outwardly bent pin-like ends to engage in any pair of opposite perforations and thus adjust the leg structure extending below the apex of the cone. 30

7. In a device as described, an inverted cone shaped wringer receptacle, a channel guide having a web and flanges, the flanges having perforations directly opposite, the web being secured to the outside of the cone receptacle and extending in a straight line between the base and the apex, a leg assembly having a pair of spaced parallel rods resiliently tending to diverge fitted between the flanges and having outwardly turned pin ends to engage any pair of perforations of 40 the flanges, a shoe connected to the lower part of the said rods to space the same and for engaging the bottom of a pail and a hook means attached to the base portion of the wringer receptacle in alignment with the channel guide and leg 45 assembly to be hooked over a rim of a pail.

8. In a device as described, an inverted cone type wringer for mops having its base uppermost and the apex being inverted, means for attaching the cone adjacent its base to a rim or the 50 like of a pail, a leg structure connected to one side of the cone and extending in a line approximately from one side of the base to the apex, the leg structure having a shoe at the bottom to engage a bottom portion of the pail remote from 55 the rim and remote from the axis of the cone, the leg structure being rigidly connected to the cone at a plurality of points and the shoe having angular bends adapted to engage the pail adjacent the bottom and the side opposite the attachment to 60 the rim.

FREDERICK A. SPEIK.
